UNITED STATES PATENT OFFICE

2,024,770

CARBON HOLDER

Charles L. Kelly, Chicago, Ill.

Application January 26, 1935, Serial No. 3,556

5 Claims. (Cl. 282—29)

The present invention relates to a holder for carbon impression sheet or the like.

Modern bookkeeping and business methods require manifold copies of many papers and particularly papers of account. Certain types of correspondence, i. e. inter-department communications in large organizations, demand a large number of impressions. Continuous strip and fanfold paper has come into use because a typist may employ such paper with higher speed than when single sheets of paper or forms are matched. Much time is consumed in matching up carbons and second sheets, as the sheets beneath the top sheet are called.

5 The present invention is particularly useful in providing a holder for sheets of carbon which may be inserted and kept between continuous rolls of paper and fanfold paper. The device is intended primarily for use upon a typewriting machine which is provided with an attachment comprising a special frame for holding rolls of strip paper or fanfold paper and for concurrently holding a carriage upon which a carbon sheet holder, herein-after described, is adapted to ride.

5 The present invention has for its objects, among others, the provision of:

An unique and improved holder for a sheet of carbon paper or the like;

A strip holder for carbon paper suited for attachment to a carriage and readily movable therewith between parallel sheets of paper; and

A new and improved carbon paper holder possessing means for connection with a carriage and having an improved means for securing the carbon paper thereon.

These objects, and such other objects as may hereinafter appear, are obtained by the novel construction, unique arrangement, and improved combination of the several elements which constitute the invention, one embodiment of which is illustrated in the accompanying single sheet of drawing, in which:

Figure 1 is a more or less schematic representation of a conventional typewriter having a frame for holding fanfold paper and for supporting the carbon paper holders herein-after described, parts of the typewriting machine and attachment being broken away to show the construction and use of the carbon holder;

Figure 2 is a plan view of a main or base strip employed in the device illustrated in Figure 1;

Figure 3 is a plan view of a member insertable into and to be used with the base strip illustrated in Figure 2;

Figure 4 is a fragmentary plan view of the end

of a sheet of carbon paper adapted to be secured upon the strips illustrated in Figures 2 and 3;

Figure 5 is a fragmentary longitudinal section of base strip, holding strip and carbon sheet;

Figure 6 is a fragmentary elevation of the same parts or elements; and

Figure 7 is a cross section on the line 6—6 of Figure 5.

Like reference characters are used to designate similar parts in the drawing and in the description hereinafter given.

Figure 1 illustrates a typewriter of conventional manufacture having at the upper back part thereof a vertical frame. The typewriter 10 comprises a keyboard 11, carriage 12, type bars 13, 15 and a frame surface 14 in carriage 12. A vertical frame members designated 15 is disposed upon support 14 and is secured to the carriage 12 in a firm manner.

Frame 15 has side members 16. Side members 16 are slotted at 17. On a track formed of said side slotted members is a transverse carriage 18 which has forwardly projecting pins 19 at each side thereof. An indicator and stop 20 is also disposed upon the frame for limiting upward movement of the carriage 18 and to indicate its relative position. The carriage 18 comprises a rear transverse member 21, the pins 19 previously mentioned, a series of carbon holding strips 22, and crossbar 23 detachably connected at the front 30 by fastening means 24 to the pins 19. The strips 22 are illustrated in Figures 2 to 7 inclusive of the drawing. The carriage also carries finger pieces 18a which arrest movement of the carriage upwardly and downwardly when the carriage engages upper stop 20 and a lower stop 20a.

The typewriter described is operated in substantially the following manner.

Fanfold paper or matched strips of paper are disposed at the rear of the typewriter. The 40 paper is designated 25 and comprises the desired number of sheets. Paper 25 is guided upwardly over the vertical frame members where it rides upon a roller or bar. The paper is then directed downwardly and around the platen 26 of the 45 typewriting machine. The forward edges of the paper are in alinement. The first and succeeding forms are in registry. The paper passes carriage 18 on its downward flight.

Carbon holding strips 22 with carbon sheets 50 attached thereto are inserted between each of the sheets of fanfold paper, the free end of the carbon depending downwardly and being movable with the paper 25 around the platen 26. Several sheets of carbon paper may be inserted between 55

parallel strips of paper. The crossbar 23 is removed to load the strips holding the carbon and is replaced before use. As desired, the carbon sheets may be first inserted anterior to fanfold paper being threaded into the machine or after it has been so threaded.

By the arrangement shown, sheets of carbon paper are positioned in uniform registry with a form about to be typed. After typed impressions 10 on the form have been completed, the pressure release lever 27 controlling the previous rolls (not shown) riding on platen 26 is actuated. The carriage 18 at the rear of the machine is then moved upwardly to a position determined by the 15 stop or pointer 20. In its movement, the carriage 18 carries with it the several carbon sheets attached to holders 22 on pins 19. Such movement will allow the lower edge of the carbon paper to be registered with the front edge of the 20 next fanfold form.

The carriage roll release lever is moved to a locked position to reestablish pressure between the paper pressure rolls and the platen 26, whereupon the previously impressed form is 25 drawn around the platen 26 and out of the machine.

As such typed form is pulled from the machine, it draws with it around the platen 26 the next succeeding form, such next succeeding form 30 having the carbon paper upon strips 22 between the several sheets thereof. The first mentioned form is then torn loose from the continuous strip along the scored lines which penetrate each of the forms in registry. The typed form is complete and the copies thereof are ready for distribution.

Typewritten impressions are then made upon the top sheet of the second form, the carbon at 40 the back thereof producing impressions upon the second sheets between the top sheet and platen 26. When the second form is typed, a repetition of the same operations is had, i. e. releasing the pressure rolls, lifting the carriage 18 and thus removing the carbon from registry with the second form into registry with the third form. Subsequently, the second form is advanced for detachment from the strip of fanfolds, and for removal from the machine, concurrently bringing the third form into position for typing.

Reference will now be had to the carbon holders 22 which form an important part of the apparatus just described. Such apparatus is but one of a number of devices in which the holders 22 may be employed.

The base or holding strip of holder 22 comprises an elongated rectangular member 30 (Figure 2) of suitable tough, flexible, and preferably unstretchable material. Cut therein by any suitable manner or means are a plurality of transverse slots. The holder 22 shown in Figure 1 has six of such slots, two (31 and 32) adjacent the center which are rather widely spaced, and two adjacent each end, 33 and 34, and 35 and 36, which are closely spaced. Grommets 37 and 38 60 are secured at the extreme corners of the strip 30 for attachment to pins 19 in the mechanism in which the carbon paper is to be used, as for example, a typewriter, a billing typewriter, an accounting machine, or a bookkeeping machine.

A second strip 40 illustrated in Figure 3 may 70 be of and generally is of lighter material than the strip 30 illustrated in Figure 2. The strip 40 comprises a central portion 41 which is substantially wider than the several slots in the first named strip. A cutout 42 for the thumb may be

formed at the lower central edge of the wide part 41 of the second strip 40. The corners 43 and 44 of the wide section of the second strip are rounded. At each side of the center 41 are elongated sections 45 and 46 with parallel sides terminating in rounded ends 47 and 48.

Carbon paper suitable for use with the two strips 30 and 40 comprises a sheet 50 of suitable texture having transferable impression material upon one or both sides thereof and over the main body of the sheet. One end 51 of the sheet preferably is free from a coating of impression material, the end 51 of the sheet comprising a section substantially double the width of the strip 30 illustrated in Figure 2. In end 51 of the carbon sheet are two series of slots in different planes, each series being in alignment and the slots being complementary to one another and complementary to the slots in the first referred to strip. The slots in sheet 50 in the upper plane 20 are designated 31 to 36, with the letter *a* attached, and those in the lower plane are designated by the same numbers with *b* attached. Complementary slots thus all have the same reference numeral and are distinguished by letters 25 or absence of letters. Only six slots 33a, 34a, 31a, 33b, 34b, and 31b show.

In use a number of carbon sheets of the proper size are selected. These are folded on a line intermediate the two series (*a* and *b*) of slots 30 therein. When so folded, the strip 30 shown on Figure 2 is inserted between the folded over portions of the carbon sheet. Registry between the several series of slots in the carbon paper 50 and in the holder 30 is obtained.

Thereupon, the second strip 40, which is highly flexible, is threaded through the slots. Member 40 is threaded into such slots by inserting its two ends 47 and 48 through the central series of slots 31 and 32 with the thumb opening down 42. Thereafter each end 47 and 48 of the second strip 40 is inserted through the end slots in the carbon paper and in the holder, i. e. one end through slots 33 and 34 and the other end through slots 35 and 36.

The enlarged body 41 of the strip 40 illustrated in Figure 3 prevents longitudinal displacement of strip 40 along strip 30, hence a firm joinder between carbon paper and carbon paper holder is obtained. Removal of the strip 40 is had by slightly flexing either strip, 30 or 40, whereupon the strip illustrated in Figure 3 is gripped between the thumb and forefinger and is withdrawn in a straight line normal to the body of the base strip 30.

Loading of a sheet of carbon paper onto a holder 22 requires but a few seconds. Removal of the holding strip is substantially an instantaneous operation. Threading a holder by grommets 37 and 38 into pins 19 requires practically no time whatever.

By the arrangement disclosed and described, any number of carbon sheets may be attached to carriage 18 for accurate registry and for movement together. The carbon sheets 50 may be of any size and (when desired) may be of varied sizes. They may be of varied colors, and they may be changed in number and arrangement at will. The care of loading and unloading is such that at all times fresh carbon sheets should be upon the carriage 18.

What is claimed as new and is desired to be secured by Letters Patent of the United States is:

1. A holder for a sheet of carbon paper, com-

prising a base strip having grommets at its corners and a series of slots therein, and a second strip inserted into the slots in said base strip.

2. A holder for a sheet of carbon paper, comprising a flexible base strip having transverse slots and an eyelet at each end, and a more flexible strip insertable into said transverse slots for holding the carbon paper on said flexible base strip.

10 3. In combination, a sheet of carbon paper, a flexible base strip, and a flexible holding strip, said sheet of carbon paper having two series of slots, said base strip having one series of slots, the two series of slots in the carbon paper coinciding with each other and with the series of slots in

said base strip when the carbon paper is folded, and the holding strip being threaded into said coinciding slots in said carbon sheet and base strip.

4. The combination described in claim 3, and 5 in which said base strip has grommets at its corners.

5. The combination described in claim 3, and 10 in which said base strip has grommets at its corner, and said holding strip is more flexible than 10 said base strip and has an enlarged central section to prevent its displacement from said base strip.
